UNITED STATES PATENT OFFICE

JOHN L. WALTERS, OF DETROIT, MICHIGAN, ASSIGNOR TO SUPERIOR SAFETY FURNACE PIPE COMPANY, A CORPORATION OF MICHIGAN

FURNACE

Application filed July 1, 1930. Serial No. 465,153.

This invention relates to furnaces of the type suitable for use in the heating of homes, and particularly to such furnaces as are of the hot air type, the principal object being 5 the provision of a construction by means of which the delivery of hot air to the various ducts leading from the furnace may be easily and quickly controlled.

Other objects are to provide a tilttable deflector or baffle member in the dome of a hot air furnace for deflecting the hot air rising into the dome in any direction desired; to provide a substantially flat baffle underlying the crown sheet of the dome of a hot air furnace and which may be tilted in any direction to deflect the heat rising into the dome to any particular desired point therein; to provide means for tilting the baffle various amounts in substantially any direction with 15 in the dome; and to provide a novel form of construction for supporting and tilting such deflector.

The above being among the objects of the present invention the same consists in certain features of construction and combinations of parts hereinafter described with reference to the accompanying drawing, and then claimed, having the above and other objects in view.

30 In the accompanying drawing which illustrates a suitable embodiment of the present invention, and in which like numerals refer to like parts throughout the several different views:

35 Fig. 1 is a front elevational view of a hot air furnace.

Fig. 2 is a plan view of the furnace shown in Fig. 1.

40 Fig. 3 is an enlarged fragmentary vertical sectional view, taken through the top of the furnace shown in Figs. 1 and 2 as on the line 3-3 of Fig. 2.

45 It is well known that where residences or like structures are heated by hot air furnaces, the tendency of the heating system is to deliver the greatest amount of hot air to those rooms on the side of the residence opposite to that from which the wind is blowing, whereas the opposite condition is usually desirable. In other words, it is usually desir-

able to have the greatest amount of hot air delivered into those rooms on the side of the residence from which the wind is blowing for such rooms are more quickly cooled and therefore require a greater amount of heat to 55 keep them at the same temperature as the rest of the residence.

I am aware that various means have heretofore been suggested for baffling or deflecting the air rising into the dome of hot air furnaces so as to enable the bulk of the air to be selectively directed into those ducts leading to the coldest rooms, and substantially all of such furnaces are provided with a damper valve in each hot air duct permitting 60 the regulation of the amount of heat passing through such ducts. However, it has been my experience that in substantially all of these constructions an undue amount of restriction is imposed on the flow of hot air 65 from the dome of the furnace into the ducts, with the result that the efficiency of the heating system is materially reduced. The baffle or deflector provided in accordance with the present invention has been designed to eliminate the disadvantages inherent in these previously suggested constructions, it is simple 70 in construction, economical to build and efficient in operation.

75 Referring to the accompanying drawing, I show in Fig. 1 what may be considered as a conventional type of hot air furnace having an outer sheet metal shell 10 terminating at its upper end in a dome 11 from which extends a plurality of ducts 12, 13, 14 and 15 80 leading to the various rooms in a residence or other building, and through which the air heated in the furnace is adapted to be delivered to such rooms. Any number of such ducts may, of course, be employed as necessity or desire dictates.

85 The shell 10 is shown as being provided with a conventional front frame 16 for the various doors such as 17, 18, 19 and 20 which lead inwardly of the shell 10 and communicate with the heating element therein generally indicated as at 21 in Fig. 3. The heating element 21 is provided with the usual stack 22 which extends outwardly through the shell 10 and which is provided for carry- 90 95 100 105

ing out the burnt products of combustion as in conventional constructions.

A dome 11 is provided with a crown sheet 25 of inverted flat cone shape as indicated, 5 the outer edges of which are secured to the upper edges of the dome 11 by a lock seam such as is indicated at 26. The crown sheet 25 is preferably covered with sand or some other insulating material such as is conventional practice to minimize the loss of heat 10 through the crown sheet 25.

In accordance with the present invention the crown sheet 25 is centrally apertured as at 31 and I secure an upwardly opening centrally apertured cup-like member 28 to the crown sheet 25 about the aperture 31 by bolts 29 and nuts 30 with the aperture in the cup aligned with the aperture 31. The purpose 20 of this cup is to prevent the insulating material 27 from passing through the opening 31 in the crown sheet 25. A post 32 projects loosely through the opening 31 and extends both above and below the upper and lower surfaces of the cup 28 and its ends are threaded. A nut 33 threaded on the post 32 abuts against the bottom of the cup and limits axial movement of the post 32 downwardly relative to the cup. Below the crown sheet 25 30 the post 32 as by nuts 36. This baffle extends into adjacent but spaced relationship with respect to the side walls of the dome 11 and, although it may be substantially flat without materially affecting its proper operation, I 35 prefer to form it slightly cone-shaped, as indicated in Fig. 3, in order to permit it to be constructed of relatively light sheet metal, and yet be relatively stiff. Furthermore, when the baffle is bent upwardly into an inverted cone shape as shown, when it is in its 40 normal or neutral position it serves to guide the hot air rising against it in a smooth and easy flow into the hot air conduits. Above the upper edge of the cup 28 and confined between two spaced pairs of nuts 37 and 38, 45 one end of an arm member 39 loosely encircles the post 32. The opposite end of the arm member 39 is provided with a pair of hook portions 40 and 41 which may be engaged over the lock seam 26 as will be later described.

In operation, the arm 39 will normally be positioned so that neither the hook 40 nor the hook 41 will engage the lock seam 26 and 55 the weight of the deflector 35 will thus cause it to hang as indicated in full lines in Fig. 3, equally disposed with relation to, all of the conduits 12, 13, 14 and 15. As a matter of illustration, let us suppose that in a residence 60 in which the furnace is employed, the wind is blowing toward the residence on the side toward which the conduit 12 leads. In such a case the arm 39 is swung around the post 32 to that side of the furnace opposite the conduit 12 and, if the wind is of medium velocity, 65

the hook 41 is engaged over the seam 26, thus causing the post 32 to tilt about that portion thereof passing through the opening 31 and causing the deflector 35 to tip upwardly on that side thereof adjacent the conduit 12 70 and downwardly on that side thereof opposite the conduit 12. The hot air then rising from the heating element 21 strikes the baffle 35 and a greater proportion thereof than normal is urged into the conduit 12, thus causing a greater flow of hot air into the conduit 12 and consequently, to that side of the house from which the wind is blowing than would normally be the case. Inasmuch as the deflector 35 stops short of the dome 11, the flow 80 of hot air to the ducts opposite the duct 12 is not blocked but only partially restricted, and those ducts between the ducts 12 and 15 are affected very little, if any, consequently, these conduits receive sufficient hot air to heat the rooms to which they extend but, of course, in lesser amounts than is received by the duct 12. If the wind is blowing extremely hard the hook 40 may be engaged over the lock seam 26 and thus cause a greater tilting of 90 the deflector 35, and consequently, a greater flow of hot air into the conduit 12 and a lesser amount into the conduits on the side of the furnace opposite the conduit 12. In a like manner, the deflector 35 may be tilted in any direction desired by simply swinging the arm 39 around to the side of the furnace opposite to that to which the greater amount of hot air is desired to be delivered, and engaged with the seam 26 to hold the deflector 35 in 100 any such adjusted position.

While I have shown the deflector 35 as being rigidly secured to the post 32, and the arm 39 as being rotatably mounted upon the post 32, it will be recognized that these features are not essential to the proper practice of the present invention as long as the deflector 35 will tilt with the post 32 and the arm 39 may be swung to any desired position around the periphery of the crown sheet 25. 110 It will also be apparent that the forming of the hooks 40 and 41 on the handle 39, for engagement with the seam 26, is a matter of economy in manufacture and, if desired, other means than the particular means shown 115 may be provided for holding the arm 39 in an adjusted position.

Formal changes may be made in the specific embodiment of the invention described without departing from the spirit 120 or substance of the broad invention, the scope of which is commensurate with the appended claims.

What I claim is:

1. In a hot air furnace, in combination, a dome, a crown sheet for said dome, a heating element under said dome, and a deflector 125 tiltably supported between said crown sheet and said element for movement in more than one plane.

2. In a hot air furnace, in combination, a dome, a crown sheet for said dome, a heating element under said dome, a deflector tiltably supported between said crown sheet and said element for bodily movement thereof, and means for holding said deflector in tilted position. 70
3. In a hot air furnace, in combination, a dome having a top sheet, a heating element under said dome, and a horizontally disposed deflector centrally supported for bodily movement between said sheet and said element. 75
4. In a hot air furnace, in combination, a dome having a top sheet, a heating element under said dome, and a horizontally disposed deflector between said element and said sheet supported for tilting movement in any direction. 80
5. In a hot air furnace, in combination, a dome having a top sheet, a heating element under said dome, a horizontally disposed deflector between said element and said sheet supported for tilting movement in any direction, and selective means for holding said deflector in any one of a plurality of tilted positions. 85
6. In a hot air furnace, in combination, a dome having a top sheet, a heating element under said dome, a horizontally disposed deflector between said element and said sheet supported for tilting movement in any direction, means for tilting said deflector various degrees in any one of a plurality of different directions, and means for holding said deflector in said tilted positions. 90
7. In a hot air furnace, in combination, a dome having a top sheet provided with a centrally disposed aperture, a post projecting through said aperture and universally movable therein, a heating element below said dome, and a deflector supported by said post between said element and said sheet. 95
8. In a hot air furnace, in combination, a dome having a top sheet provided with a centrally disposed aperture, a post projecting through said aperture and universally movable therein, means limiting axial movement of said post downwardly, a heating element below said dome, and a deflector supported by said post between said element and said sheet. 100
9. In a hot air furnace, in combination, a dome having an inverted cone shaped top sheet, a cup shaped member centrally secured to said sheet, the bottom of said cup and said sheet having aligned apertures, a post projecting through said apertures, and universally adjustable therein relative to said top sheet, an approximately flat deflector secured to said post below said sheet, and an arm engaging said post above said sheet for holding said post in adjusted position. 105
10. In a hot air furnace, in combination, a dome having an inverted cone-shaped top sheet, a cup-shaped member centrally secured to said sheet, the bottom of said cup and said sheet having aligned apertures, a post projecting through said apertures and universally adjustable therein relative to said top sheet, an approximately flat deflector secured to said post below said sheet, and an arm engaging said post above said sheet for holding said post in adjusted position. 110
11. In a hot air furnace, in combination, a dome having an inverted cone-shaped top sheet, a cup-shaped member centrally secured to said sheet, the bottom of said cup and said sheet having aligned apertures, a post projecting through said apertures and universally adjustable therein relative to said top sheet, an approximately flat deflector secured to said post below said sheet, and an arm engaging said post above said sheet and swingable about the central axis of said dome for holding said post in adjusted position. 115
12. In a hot air furnace, in combination, a dome having an inverted cone-shaped top sheet provided with a central aperture, heat insulating material covering said sheet, an upwardly extending annular flange on said top sheet surrounding said aperture for preventing passage of said material therethrough, a post projecting through said aperture and universally movable relative to said top sheet, a heating element below said dome, and a deflector secured to said post between said element and said top sheet and movable therewith. 120
13. In a hot air furnace, in combination, a dome having a top sheet provided with a centrally disposed aperture, a post projecting through said aperture and universally movable therein, a heating element below said dome, ducts extending outwardly from said dome, and a deflector supported by said post between said element and said sheet for regulating the relative flow of hot air from said element into said ducts. 125
14. In a hot air furnace, in combination, a sheet metal dome having a top sheet joined thereto by a seam forming an externally projecting bead, a heating element under said dome, a post projecting centrally through said top sheet and universally movable relative thereto, a deflector secured to said post between said element and said top sheet, an arm secured to said post above said top sheet and having an end projecting into adjacent relationship with respect to said bead, and catches on said arm engageable with said bead for holding said post in moved position. 130
15. In a hot air furnace, in combination, a dome, a crown sheet for said dome, a heating element under said dome, an inverted cone-shaped deflector tiltably supported between said crown sheet and said element, and means for holding said deflector in tilted position. 135
16. In a hot air furnace, in combination, 140

a dome having a top sheet provided with a centrally disposed aperture, a post projecting through said aperture and universally movable therein, a heating element below said dome, and an upwardly and outwardly extending deflector centrally supported by said post between said element and said sheet.
